UNITED STATES PATENT OFFICE

CHARLES D. SEEBERGER, OF YONKERS, NEW YORK, ASSIGNOR TO OTIS ELEVATOR COMPANY, A CORPORATION OF NEW JERSEY.

CONVEYER.

1,043,542.

Specification of Letters Patent.

Patented Nov. 5, 1912.

Application filed March 10, 1906, Serial No. 305,206. Renewed March 16, 1910. Serial No. 549,738.

To all whom it may concern:

Be it known that I, CHARLES D. SEEBERGER, a citizen of the United States, residing at Yonkers, in the county of Westchester and State of New York, have invented certain new and useful Improvements in Conveyers, of which the following is a specification, reference being had therein to the accompanying drawings.

10 This invention has reference to conveyers, and particularly to that type of conveyers in which a traveling footway, preferably in the form of a series of connected steps, extends between different levels for transporting freight or passengers therebetween.

15 The invention has for its objects generally to provide certain novel and useful improvements in this class of machines, and it consists in the organizations and arrangements 20 of parts hereinafter particularly described and then pointed out in the appended claims.

In the accompanying drawings—Figures 1 and 2 together show diagrammatically and partially in elevation the general arrangement of a traveling footway embodying my invention, Fig. 1 illustrating the lower end of the machine and Fig. 2 the upper, the intermediate portion of the incline being broken out for convenience of illustration. 25 Fig. 3 is a transverse sectional view on the line 3—3 of Fig. 2; Fig. 4 is a similar view on the line 4—4 of Fig. 2, showing the rear wheel of one step seating upon the front wheel of the following step; Fig. 5 is a plan view showing the terminals of the tracks for the rear wheels at the upper landing; Fig. 6 is a diagrammatic side view showing the location of the drive and associated up-thrust, and also an intermediate idler which 30 may be employed; Fig. 7 is a view in side elevation, and on an enlarged scale, showing the up-thrust and step-linkage co-operating therewith; Fig. 8 is a central transverse sectional view through the up-thrust; Fig. 9 is 35 a detail plan view of the take-up idler employed with the up-thrust; Fig. 10 is a detail view in side elevation of the intermediate idler shown in Fig. 6; Fig. 11 is a plan view of the construction shown in Fig. 10; Fig. 40 12 is a detail sectional view of the idler, with its sliding bearing; Fig. 13 is a detail view of the step-linkage; Fig. 14 is a sectional view on the line 14—14 of Fig. 13 looking in the direction of the arrows; and

Fig. 15 is a view in cross section of a traveling handrail.

In the form of machine illustrated, the steps 20, providing the footway, and which may be provided with the usual treads and risers, travel at the lower level with their tread surfaces in the same horizontal plane to provide a moving landing 21, and after breaking into step-like formation and traveling along the incline, again run in a horizontal plane to form an upper landing 22. In the present disclosure the machine is assumed to transport in an ascending direction, although it is obvious that its direction of movement may be reversed so as to transport in a descending direction. At the lower level a horizontal track 23 is located at each side of the machine, and this track extends at an incline to the upper level where it again assumes a horizontal position. An upper track 24 on each side originates above its associated lower track at a point adjacent the inner end of the lower landing 21, and gradually curving away from the lower track continues at a suitable elevation above and parallel with the lower track along the incline, terminating at the entrance of the upper landing 22 where it curves toward the lower track, the ends of the track 24 being at the same distance above the track 23. In the present embodiment of the invention the tracks overlap in the same vertical plane, the upper track 24 extending outside of the track 23, as shown in Figs. 3 and 4. These tracks, as there shown, may be formed from a single casting and connected by a web or bracket 25 which may be suitably secured to the supporting frame, or they may be separately carried on the frame.

The lower tracks 23 receive the front wheels 26 of each step, assuming the footway to ascend on its transporting run, while the rear wheels 27 co-operate with the upper tracks 24. Beyond the upper landing the steps pass through a suitable carriage 28 which is provided with a curved extension 29 of the track 23 and which with a track 30 provides a channel for the front wheels of the steps. A similar channel, consisting of a curved track 31 and a guard track 32, is provided for the wheels 27. The trackage 100 for the return run of the footway consists of overlapping tracks 33 and 34, the arrangement of the tracks being reversed so that the

5 tracks 33 for the rear wheels are below the tracks 34 for the front wheels to correspond with the reversal of the steps; the tracks 33 are continuations of the tracks 31, and extend horizontally at their ends under the upper and lower landings. The lower end of the track 33 is curved upwardly and terminates slightly beyond its horizontal portion.

10 At the lower end of the machine the steps pass through a carriage 35 having at each side a curved track 36 for the front wheel 26 and in extension of the track 23, the entrance to such extension having a curved guard 15 track 37, while a curved track 38 serves to carry the rear wheels 27 through the carriage.

From the foregoing it will be observed that at each landing only a single track is 20 employed at each side of the machine, while along the inclines the trackage consists of upper and lower tracks. The terminals of each of the tracks 24 and 34 are reduced in width for a suitable distance and are so 25 spaced from the lower tracks 23 and 33 that the upper portions of the lower wheels come flush with the treads of the terminals, as shown in Fig. 4. It is obvious that the terminals of the tracks at the entrance and exit 30 of each carriage may be arranged in the same manner. It is also obvious that the form of the tracks may be varied for accomplishing this result without departing from my invention.

35 In the present embodiment of the invention each step is provided with an axle bar 39 on the ends of which are pivoted the front wheels 26 adapted to the inner tracks 23 and 34. This axle bar is suitably secured to the 40 step-frame as by pins 40 and is located at the side opposite the riser. A yoke or arm 41 is suitably secured, as by means of a pin 42, to the axle bar inside of each wheel 26 and is spaced from the step-frame a suitable distance, as shown in Figs. 4 and 5, for the purpose to be hereinafter pointed out. Each 45 arm preferably extends beyond the step-riser and has pivoted at its free end the outer wheel 27, the arm being deflected or bent outwardly so as to locate the rear wheel in position to coöperate with its associated track. Each arm 41 is inclined upwardly with reference to the tread of the step, and the tracks on the inclines are so related that 50 when the step wheels engage the same the treads will be maintained in horizontal position. The length of each arm is such that the rear wheel 27 thereon is, at the landings on the transporting run, located over the 55 front wheel 26 of the following step, and on the return run under the wheel 26 of the following step.

With the arrangement of tracks described the front wheels 26 are in engagement with 60 the lower tracks 23 throughout the trans-

porting run, and on the incline the rear wheels 27 travel on the tracks 24. At the landings, however, on the transporting run, the rear wheels 27 of each step seat themselves upon and are supported by the front 70 wheels of the following step, as shown in Figs. 1 and 2. The structure delineated in these figures being duplicated on the other side of the machine, it will be apparent that as each step passes to the lower landing 21 75 the front wheels 26 thereof come flush with the treads of the tracks 38 so that the inner overlapping edges of the rear wheels 27 of the step in advance, as the latter wheels leave the track 38, will seat upon 80 the wheels 26. The wheels 27 while thus supported turn freely so as to avoid friction, and they preferably are made without flanges. Adjacent the curve at the bottom of the incline, the rear wheels pass to the track 85 24, and the relation of the tracks cause the footway to break into and continue in step-like formation to the upper end of the incline. At the terminal of the track 24 at the upper landing the rear wheels of each step 90 again seat upon the front wheels of the following step and are supported thereby as the steps move along the upper landing. In passing through the upper carriage the arrangement is reversed, and the wheels 26 seat 95 upon the wheels 27 and are supported thereby until they enter the upper track 34 on the return run. At the bottom of the return run the wheels 26 again seat upon the wheels 27 and are supported thereby until the steps 100 enter the lower carriage, by which the steps are presented to the transporting run with their treads uppermost.

The steps are connected by suitable links 105 43 which are pivoted to the axle bars between the attached ends of the arms 41 and the step-frames as shown in Fig. 5. Each link as shown in Figs. 13 and 14 is provided with a bifurcated sleeve 44 at one end, and a collar 45 at the opposite end, and a bushing 110 46 passes through the associated sleeve and collar and is loosely mounted on the axle bar between the yoke and end of the step-frame. In assembling the parts the collar of one link is entered in the bifurcation of another link and the bushing is then inserted and secured to the bifurcated ends or sleeve. With this arrangement the collar is free to 115 turn on the bushing, and as the bushing turns on the axle the other end of the link is capable of pivotal movement on the axle as the step passes the curves or travels through the carriages at the ends of the machine. The links are provided with teeth, and in order to prevent interference 120 between the end teeth of the links at the points where the direction of movement is changed, the tooth at the bifurcated end of each link is split, one half 47 being formed on each side of the bifurcated end. This 125 130

permits the end teeth to overlap without interference and at the same time preserves the continuity of the teeth. As shown in Figs. 7 and 10 the links are provided with 5 bosses 48 over the pivotal points thereof for a purpose hereinafter described. In the present arrangement these bosses are formed on the bifurcated ends of the links, although they may be located on the collars 45.

10 The steps may be driven in any suitable manner, as by means of sprockets 49 fixed to a suitably driven cross-shaft 50 and engaging the rack links of both runs, preferably near the upper end of the incline. The 15 sprockets 49 may be in the form of lantern wheels having anti-friction rollers 51 on the spindles 52 thereof, as shown in Fig. 7.

The action of the driving sprockets tends to lift the steps and also turn the links upon 20 their pivots as they engage the extreme teeth thereon. To counteract this action, a suitable upthrust is provided. This upthrust is located at the side of the linkage opposite the sprocket engaging the associated 25 line of linkage. In the present instance this upthrust consists of an endless chain 53, which is carried by end idler sprockets 54 located at opposite sides of the shaft 50, as shown in Fig. 7. The idlers are fixed to 30 shafts 55 suitably journaled in brackets 56 supported by the frame work of the machine. The chain 53 is composed of alternate male and female shrouds 57 and 58, respectively. The male shrouds 57 are channel shape in cross section, as shown in Fig. 35 8, and the female shrouds are provided with ears 59 which overlap the male shrouds and receive pivot pins 60 passing through suitably aligned apertures in the male and female 40 shrouds. These pins are provided with rollers 61. This construction provides a practically continuous surface or face along the under stretch of the chain. As shown in Figs. 7 and 8 the side walls of the male 45 shrouds project beyond the female shrouds so as to embrace a guide 62, which in the present instance is located above the operative stretch of the chain and parallel with the line of movement of the step linkage. 50 This guide is carried by brackets 63 suitably secured to the frame work of the machine, and acts as a bearing surface or abutment for the chain when the links engage its opposite face. In order to maintain the chain 55 under proper tension, a tightener sprocket 64 is mounted in a sliding block 65 provided at its ends with ribs 66 engaging suitable guide ways 67 in the brackets 63. Expansion springs 68 reacting between the track 60 and the block serve to press the tightener upwardly thereby automatically taking up the slack in the chain. As the drive-links connecting the steps come under the action of the driving pinion any tendency of the 65 steps to rise or of the links to tilt or turn

is counteracted by the engagement of the bosses 48 with the upthrust chain, and as such chain is entirely supported by idlers, it provides a traveling upthrust which is freely movable in the same direction as and under the action of the drive-links. The 70 guide 62 provides a rigid abutment to receive the thrust of the chain, and as the chain is movable under the action of the links and is provided with antifriction rollers in engagement with the guide, the friction and wear between the parts are reduced to a minimum. In another aspect, the guide or track forms the abutment or real upthrust, and the chain reduces the friction 75 between the upthrust and the links.

With the driving sprockets located near the upper end of the machine the strain on the sprockets, due to the dead load or weight of the steps and connections between such 80 sprockets and the bottom of the incline, is very great, and in long machines it is highly objectionable owing to the great wear on the sprockets. I provide means for reducing the load on the drive sprockets, and to 85 this end I introduce idlers 70 between the drive sprockets and the bottom of the incline. By this arrangement, the weight of the steps on each run between the point where the idlers 70 are located and the bottom of the incline is carried by such idlers, while only the weight from the idlers 70 to the drive sprockets is placed on the latter 90 sprockets. In the present case I show but a single instance of such idlers, but it is obvious that these may be duplicated and located at suitable intervals so that a plurality of such weight-dividing means may be employed. In the present embodiment, these 95 idlers are mounted on a cross-shaft 71, and engage the upper and lower lines of links at the adjacent sides. The shaft 71 is journaled in bearing blocks 72 supported by longitudinal beams 73, which in turn are supported by transverse beams 74. While these 100 idlers may be of any suitable character I have shown them in the present instance as lantern wheels, the spindles thereof being provided with antifriction rollers 75. The bearing blocks are slidably mounted on 105 guide plates 76 bolted to the beams 73; and each guide plate is provided with an ear 77 having an aperture passing therethrough, and a rod 78 passes through the aperture 110 and is in threaded engagement with the bearing block. A coil spring 79 is interposed between the ear and the bearing block, and such spring normally tends to move the bearing block toward the drive sprockets 49, the movement in this direction being limited 115 by a stop nut 80 threaded upon the rod. The springs 79, by pressing the idlers in a direction opposed to the weight or hang of the stairway, hold the teeth thereof against the 120 teeth of the links when then hang thereon, 125 130

and such springs are adjusted to a resistance corresponding to the normal load, due to the weight of the steps and connections supported thereby.

5. It will be obvious from the foregoing that the springs act as a counterbalance for the load supported thereby, and that when subjected to strains in excess of such load will yield, thus taking care of inequalities of motion.

10. It will also be obvious that instead of springs any other suitable means may be employed as a counterbalance, as, for example, a suspended weight.

15. In Fig. 15 a cross section of a traveling hand-rail 81 is shown which may be employed with the stairway. This hand-rail is preferably C-shape in cross-section and consists of a strip of suitable material, such as canvas, folded back and forth upon itself to provide a number of layers or plies 82, the folds 83 between the plies being located at the cross-sectional ends of the rail. In the present instance the edges 84 of the 25 strip terminate adjacent the same cross-sectional end of the rail with the folds thereat located between such edges. A separate wear strip 85 covers the internal face of the rail and also the folds 83 and edges 84 to 30 protect the same from wear. The canvas or other fabric may be coated with, cemented together by, or embedded in suitable material, such as rubber, as indicated by dotted lines in Fig. 15, as is usual in this class of 35 devices.

Having described my invention what I claim is—

1. In a device of the class described, a way, and a series of steps each having wheel-carrying arms coöperating with an adjacent step at a certain portion of the way to maintain the tread of the step horizontal.

2. In a device of the class described, a way, and a series of wheeled-steps adapted thereto, the wheels at one side of each step coöperating with an adjacent step to maintain its tread horizontal.

3. In a device of the class described, a way, and a series of wheeled-steps traveling thereon, one wheel of each step being seated on the wheel of an adjacent step at a certain portion of the way.

4. In a device of the class described, a way, and a series of steps having carrying-wheels one wheel of each step being loosely seated on a wheel of an adjacent step at a certain portion of the way.

5. In a device of the class described, a way, and a series of steps adapted to the way and having front and rear carrying-wheels, one pair of wheels of each step being seated on wheels of an adjacent step at certain portions of the way.

6. In a device of the class described, upper and lower ways connected by inclined

ways, a series of steps adapted to the ways and having front and rear carrying wheels, the front wheels of each step supporting the rear wheels of an adjacent step on one way and the rear wheels supporting the front wheels of an adjacent step on the other way to maintain the treads of the steps horizontal.

7. In a device of the class described, inclined tracks one of which is provided with a horizontal landing portion, a series of steps having wheels engaging both tracks on the incline, the trackless wheels at the landing being supported by the other wheels.

8. In a device of the class described, a way consisting of upper and lower inclined tracks the lower track having horizontal landing portions, a series of steps each having upper and lower wheels coöperating with the upper and lower tracks, respectively, on the incline and the upper wheels of each step seating on the lower wheels of an adjacent step at the landing portions.

9. In a device of the class described, a way consisting of upper and lower inclined tracks, the lower track having horizontal landing portions and the upper tracks terminating beyond the ends of the incline, a series of steps having front and rear wheels, the latter engaging the lower tracks throughout the length thereof and the former seating on the front wheels at the landing portions.

10. In a device of the class described, a way consisting of lower inclined tracks having horizontal end portions and upper tracks parallel with the lower tracks at the incline and terminating beyond the ends of the incline, the upper track at each side overlapping the lower track, of steps having front and rear wheels adapted to the lower and upper tracks, respectively, the rear wheels seating on the front wheels at the horizontal portions.

11. In a device of the class described, a way consisting of upper and lower inclined tracks overlapping in the same vertical plane and connecting different levels, the lower tracks having horizontal landing portions and the upper tracks extending beyond the ends of the incline and being reduced in width at the terminals, and a series of steps having front and rear wheels adapted to the lower and upper tracks, respectively, the rear wheels of each step being seated on the front wheels of the following step at the levels and gradually passing to or from such wheels at the reduced terminals of the upper tracks.

12. In a device of the class described, a way consisting of upper and lower inclined tracks overlapping in the same vertical plane and connecting different levels, the lower tracks having horizontal landing portions and the upper tracks extending beyond the

- ends of the incline and being reduced in width at the terminals, and a series of steps each of which is provided with axle bars and rearwardly and upwardly inclined yoke-arms, wheels on the axle bars and the ends of the yoke arms adapted to the lower and upper tracks, respectively, the rear wheels of each step being seated on the front wheels of the following step at the horizontal landings, and gradually passing from or to such wheels at the reduced terminals of the tracks associated therewith.
13. In a device of the class described, trackage for the upper and lower runs of a traveling stairway connecting different levels, steps having front and rear wheels adapted to the trackage, the front wheels of each step at the levels of the upper run supporting the rear wheels of the preceding step and the rear wheels supporting the front wheels of the succeeding step at the levels of the lower run.
14. In a device of the class described, trackage for the upper and lower runs of a traveling stairway, the trackage for each run consisting of upper and lower inclined tracks, the lower tracks having horizontal ends connected by carriages for changing the direction of movement of the stairway, steps having front and rear wheels adapted respectively to the lower and upper tracks on the upper run, and to the upper and lower tracks on the lower run, the front wheels of each step supporting the rear wheels of an adjacent step on the horizontal on the upper run and the rear wheels supporting the front wheels of an adjacent step on the lower horizontal run.
15. In a device of the class described, a series of steps having front and rear wheels, a way having inclined and horizontal portions providing a track for each wheel at the incline and for the front wheels only at the landings, at which points the rear wheels of each step are seated on the front wheels of an adjacent step.
16. In a device of the class described, a traveling stairway providing upper and lower runs and consisting of a series of connected steps having front and rear pairs of wheels, yoke arms on which the rear wheels are pivoted, and tracks for the runs consisting of a track for both pairs of wheels on the incline and for one pair of wheels only of each step at the landings, the other pair of wheels being supported by the wheels of an adjacent step.
17. In a device of the class described, a way having upper and lower horizontal portions and an intermediate inclined portion, upper and lower tracks on the inclined portion, a single track on each of the horizontal portions, and a series of sections moving on the tracks and being intersupporting on the horizontal portions of the way.
18. In a device of the class described, a way having upper and lower horizontal portions and an intermediate inclined portion, upper and lower tracks on the inclined portion, a single track on each of the horizontal portions, and a series of steps moving on the tracks, each step supporting an adjacent step on the horizontal portions of the way.
19. In a device of the class described, a way having upper and lower horizontal portions and an intermediate inclined portion, upper and lower tracks on the inclined portion, a single track on each of the horizontal portions, a series of steps moving on the tracks, and front and rear wheels on each step running on the inclined tracks and one set thereof bearing on adjacent steps on the horizontal tracks.
20. In a device of the class described, a step having front and rear wheels, the rear wheel at each end of the step overlapping the corresponding front wheel in the same vertical plane, and tracks for the wheels.
21. In a device of the class described, a step having front and rear wheels the latter being above the former and overlapping the same in a vertical plane, and tracks for the steps.
22. In a device of the class described, a series of steps having front and rear wheels the latter being below the former in a vertical plane, upper and lower tracks to which the upper and lower wheels, respectively, are adapted, the lower tracks having inclined portions which extend horizontally at the ends, and the upper tracks being spaced a greater distance from the lower tracks on the incline than the diameter of the wheels and being reduced in width at the ends and terminating with the tread surface thereof a distance from the lower tracks equal to the diameter of the wheels, whereby as the rear wheels of each step leave the upper tracks they seat upon the front wheels of the following step.
23. In a device of the class described, a way, a series of connected steps having front and rear wheels, yoke arms on which the rear wheels are pivoted and which are of such length as to locate the wheels thereof above the front wheels of the following step, and tracks having terminals for seating the rear wheels of a step on the front wheels of the adjacent step as the steps pass from the incline to the horizontal.
24. In a device of the class described, upper and lower ways connected by end-carriages, a series of connected steps having front and rear wheels, yoke arms on which the rear wheels are pivoted and which are of such length as to locate the wheels thereof in position to rest upon or receive the wheels of the following step on the upper and lower ways, respectively.
25. In a device of the class described, a

way having inclined and horizontal portions providing upper and lower tracks, a series of steps having front and rear wheels running on the tracks, the tracks being uniformly spaced apart in the incline and at a greater distance apart than the diameter of the wheels, and the upper tracks at the horizontal portions approaching the lower tracks and terminating in the plane of the upper portions of the wheels on the lower track.

26. In a device of the class described, upper and lower ways connected by end-carriages, a series of connected steps having front and rear wheels, upwardly inclined yoke arms on which the rear wheels are pivoted and which are of such length as to locate the rear wheels of each step above or under the front wheels of the following step as the steps move in a horizontal direction on the upper and lower ways, respectively, each way consisting of upper and lower inclined tracks, the front and rear wheels on one way being adapted to the upper and lower tracks, respectively, and to the lower and upper tracks on the other way, the lower tracks having horizontal ends and the upper tracks terminating beyond the ends of the inclines in position to lead the wheels traveling thereon to or to receive them from the wheels in engagement with the lower track of each way.

27. In a device of the class described, a series of steps each of which is provided with an axle-bar having wheels fixed thereto, wheel-carrying yoke-arms on the axle-bar and spaced from the ends of the steps, and linkage connecting the axle-bars between the yokes and the ends of the steps, the links having the teeth thereof in line.

28. In a device of the class described, a series of steps, each step having an axle bar and being provided with carrying wheels, and rack-links connecting the axle bars, each link having a bifurcation at one end receiving the adjacent end of another link to bring the teeth of the links in line.

29. In a device of the class described, a series of steps, each having an axle bar and being provided with carrying wheels, and rack links each of which is provided with a bifurcation at one end receiving the opposite end of the adjacent link.

30. In a device of the class described, a step having an axle bar and carrying-wheels, a pair of links one of which is provided with a bifurcated sleeve and the other with a collar entering the bifurcation to bring the teeth of the links in line, the axle bar passing through the said sleeve and collar.

31. In a device of the class described, a series of steps each having an axle bar and carrying-wheels, rack-links each of which is provided at one end with a bifurcated sleeve and at the other with a collar, a bushing loosely mounted on each axle and to which

the collar of a link is fixed, the bifurcated end of the adjacent link being pivoted on the bushing and receiving the collar of the other link.

32. In a device of the class described, a series of steps provided with axle bars and carrying-wheels, bushings on the axle bars, and links connecting the axle bars, one of such links having a collar pivoted on the associated bushing and the other a bifurcated sleeve fixed on the bushing and receiving the collar, the sleeve having a tooth disaligned from the other teeth whereby the continuity of the teeth is preserved and pivotal movement of the links is permitted without interference of the end teeth of adjacent links.

33. In a device of the class described, steps having axle bars and links connecting the axle bars, the connection between adjacent links consisting of a collar on one link and a bifurcated sleeve on the other receiving the collar, the said sleeve and collar having pivotal movement on the axle bar, and the end tooth of the former link being split and located on the sleeve at opposite sides of the collar, whereby the continuity of the teeth is preserved and pivotal movement of the links permitted.

34. In a device of the class described, a conveyer, and an upthrust movable uniformly in the direction of the conveyer.

35. In a device of the class described, a conveyer, and an upthrust movable under the action of and uniformly in the direction of the conveyer.

36. In a device of the class described, a conveyer, and an upthrust adapted to co-operate with and be moved uniformly in the direction of the conveyer.

37. In a device of the class described, an endless upthrust movable freely under the action of the conveyer.

38. In a device of the class described, an endless upthrust consisting of a chain having a flat contact surface.

39. In a device of the class described, a series of link connected steps, a driving wheel engaging the links to drive the steps, and an endless upthrust with which the links are adapted to co-operate under the action of the wheel, and idlers for the chain.

40. In a device of the class described, the combination with a series of link connected sections, a wheel engaging the links to drive the sections, and an upthrust to counteract the lifting and tilting action of the driving wheel and comprising a rigid abutment parallel with the normal line of movement of the links and a friction reducing traveler between the links and the abutment.

41. In a device of the class described, the combination with a series of link connected sections, a wheel engaging the links to drive

the conveyer, a rigid abutment over and parallel with the line of movement of the links, and a chain between the links and the abutment and having rollers engaging the latter.

42. In a device of the class described, a series of steps, rack links connecting the steps, a driving wheel engaging the links to move the steps, and an upthrust to resist the lifting and tilting action of the driving wheel, and consisting of a freely movable endless chain having the lower stretch thereof parallel with the direction of movement of the links.

15 43. In a device of the class described, a series of steps, rack links connecting the steps, a sprocket engaging the links to move the steps, and an upthrust to resist the lifting and tilting action of the sprocket, and 20 consisting of an endless chain having the lower stretch thereof parallel with the direction of movement of the links, and a guide for such stretch of the chain.

44. In a device of the class described, a series of link connected steps, bosses on the links, a sprocket engaging the links to drive the steps, an endless upthrust chain located above the links and normally out of engagement with the bosses, idlers for the chain, 30 and a guide for the stretch of the chain adapted to coöperate with the bosses.

45. In a device of the class described, a conveyer, an endless upthrust therefor, and a tension device for the upthrust.

35 46. In a device of the class described, a conveyer, an upthrust therefor consisting of an endless chain, and a tension device for the chain.

47. In a device of the class described, a series of link-connected steps, a driving sprocket engaging the links, and an upthrust consisting of an endless chain with which the links are adapted to coöperate under the action of the sprocket, idlers by 45 which the chain is carried, and a spring pressed take-up idler engaging the chain.

48. In a device of the class described, a series of link connected steps, a sprocket engaging the links, and an upthrust consisting of a chain located over and parallel with the line of movement of the links, a guide track for the stretch of the chain adapted to coöperate with the links, idlers by which the chain is carried, and a tension device for the chain.

49. In a device of the class described, a series of link-connected steps, a sprocket engaging the links, and an upthrust consisting of a chain located over and parallel with the line of movement of the links, a guide track for the stretch of the chain adapted to coöperate with the links, idlers by which the chain is carried, and a tension device for the chain consisting of a spring pressed idler.

55 50. In a device of the class described, a

series of link-connected steps, a sprocket engaging the links, and an upthrust consisting of a chain composed of alternating male and female shrouds, pivot pins connecting the links, rollers on the pins, and a guide 70 track engaged by the rollers on the under stretch of the chain.

51. In a device of the class described, a series of link-connected steps, a sprocket engaging the links, and an upthrust to resist the lifting and tilting action of the pinion and consisting of an endless chain composed of male and female shrouds, pivot pins connecting the links, rollers on the pins, and a guide track for the under stretch 75 of the chain, the male shrouds being channel shape in cross-section and embracing the track.

52. A conveyer having ascending and descending runs, a drive for the conveyer, and an upwardly pressed idler engaging both runs to counterbalance the drag or load of the conveyer below the same.

53. In a device of the class described, a conveyer having inclined runs, a drive for 80 the conveyer, and a spring pressed idler engaging both runs on the incline.

54. A conveyer having ascending and descending runs, a drive for the conveyer, and a spring controlled idler engaging both runs, 85 the tension of the spring being set to correspond to the load on the idlers and being adapted to yield to strains greater than such load due to inequalities of motion.

55. In a device of the class described, a 90 conveyer having inclined runs, a drive engaging both runs, an idler engaging both runs between the drive and the end of the incline, and a spring for pressing the idler up the incline so that the weight of the conveyer below the same will hang thereon.

56. In a device of the class described, a way having an inclined and horizontal runs, and a series of steps having bearings traveling on the way and each step being partially supported by an adjacent step on the horizontal runs.

57. In a device of the class described, a way having an inclined and horizontal runs, a series of steps each having front and rear carrying-wheels at each end, and the wheels of each step traveling on the way on the inclined run and one wheel on each end of each step being carried by a wheel of an adjacent step on the horizontal runs.

58. In a device of the class described, a conveyer consisting of an endless series of link-connected steps providing ascending and descending inclined runs, drive sprockets engaging the links of both runs on the incline, idler sprockets located at the incline and engaging the links on both runs, and springs for moving the idlers in opposition to the hang of the steps down the incline.

59. In a device of the class described, a

conveyer consisting of an endless series of link-connected steps providing ascending and descending inclined runs, a drive shaft located near the upper end of the incline having sprockets engaging the links of both runs, an idler located between the drive shaft and the bottom of the incline and engaging the links of both runs, a sliding bearing for the idler, and an adjustable spring reacting against the bearing to hold the idler in engagement with the link teeth in opposition to the hang of the steps.

60. In a device of the class described, ways, a moving stairway consisting of 15 wheeled steps traveling on the ways and providing ascending and descending inclined runs, rack-links connecting the steps at each end thereof, a drive shaft having sprockets engaging the links of both runs 20 at each end of the steps, a shaft located between the drive shaft and one end of the incline and having idler sprockets engaging the links of both runs, springs for moving the idlers in opposition to the weight of the 25 steps hanging thereon, such springs being set at a tension corresponding to the load on the idler sprockets, and means to vary the tension of the springs.

61. In a device of the class described, a 30 way, a moving stairway consisting of wheeled steps traveling on the way and providing ascending and descending inclined runs, rack links at the sides of the stairway connecting the steps, a drive shaft adjacent the upper end of the incline and having sprockets engaging the links of both runs, a cross shaft between the drive shaft and the bottom of the incline and having idlers engaging the links of both runs, sliding

blocks in which the said shaft is mounted, 40 ears rigid with the frame having openings, rods passing through the openings and engaging the blocks, springs on the rods and reacting between the ears and blocks, and nuts on the rods to vary the tension of the 45 springs.

62. A hand-rail substantially C-shape in cross-section and consisting of a strip of material folded into a plurality of plies and having its edges terminating at the 50 same cross-sectional end of the rail, and a separate wear strip crossing both of such ends.

63. A hand-rail substantially C-shape in cross-section and consisting of a single strip 55 of material folded back and forth to provide a plurality of plies having the folds at the cross-sectional ends of the rail, the edges of the strip terminating at one of such ends, a separate wear strip covering the interior of the rail and also the said ends, and a coating for the rail.

64. A hand-rail substantially C-shape in cross-section and consisting of a strip of material folded back and forth to provide 65 a plurality of plies and having the folds at one of the cross-sectional ends between the edges of the strip, a separate wear-strip covering both of such ends and the interior of the rail, and a body, such as rubber, connecting the strips.

In testimony whereof I affix my signature in presence of two witnesses.

CHARLES D. SEEBERGER.
